DISPENSER FOR DENTAL INGOTS
Richard Hospe, Huntington, N.Y., assignor to Julius Aderer, Inc., Long Island City, N.Y., a corporation of New York

Filed Mar. 13, 1967, Ser. No. 622,786
10 Claims. (Cl. 312—61)

ABSTRACT OF THE DISCLOSURE

A dispenser for dental ingots having an enclosure for holding a plurality of stacked flat dental ingots, and a spring-driven plunger for advancing the stack as each leading ingot is slid edgewise from the front of the stack by finger-contact until it is emitted from the dispenser. A window is provided adjacent the ingot dispensing aperture, so that the ingots remaining in the dispenser can be viewed. The plunger is formed so as to hide the spring from view through the window, to allow no more than a predetermined maximum quantity of ingots to be initially inserted into the dispenser, and to allow a quick visual estimate through the window of the proportion of initial ingots remaining in the dispenser by the ratio of visible ingots to visible plunger.

Background of the invention

In dental laboratories where dentures are custom manufactured, the dental technicians must be supplied dental ingots of precious metal (e.g. dental gold) for fabrication of the denture parts, such as crowns, bridges and the like.

It is easy to lose or misplace the dental ingots, which are generally flat squares a fraction of an inch on a side, and perhaps one-thirtieth of an inch in thickness. It is also easy to pilfer them for the same reason. Moreover, the dental technician needs a means of keeping track of how many ingots he has used during a given period, and he needs ample warning as to when to secure more from stock or his source of supply so that he is not caught short of ingots without realizing it.

What is needed in the dental ingot use field then, is a dispenser that prevents loss of ingots, keeps them handy before and during use, and allows ample warning of depletion so that more can be secured.

Brief summary of the invention

A dispenser is provided for holding a plurality of stacked dental ingots. A plunger and spring combination within the dispenser is so arranged in form and proportions that the spring cannot be seen through a window in the dispenser, yet all the ingots within the dispenser can be seen.

As the ingots are dispensed by manual sliding of the leading ingots, one by one, out a lateral slot in the dispenser, the plunger advances proportionately. At all times then, the proportion of ingots remaining can be quickly estimated through the window by comparing the remaining stack length visible therethrough to the length of plunger visible therethrough.

If desired, the plunger proportions can be further arranged so that when the plunger is bottomed to admit the greatest number of ingots in initial loading, a predetermined number will be accommodated so that counting at initial loading is unnecessary.

The dispenser according to the invention is very simple and economical to manufacture, and so can be employed as the retail package for the ingots as well as the dispenser therefor.

2

Brief description of the figures

An illustrative embodiment of the invention is set forth hereinbelow in a detailed description of the invention with reference to the figures, in which:

FIG. 1 is a perspective view of a dispenser according to the invention showing a dental ingot in the process of being slidably emitted from the dispenser in the direction indicated by the illustrative arrow thereon;

FIG. 2 is an exploded perspective view of the parts shown in FIG. 1;

FIG. 3 is a section view taken along plane 3—3 of FIG. 1 showing internal details of construction of the dispenser;

FIG. 4 is an end view of the dispensing end shown in FIG. 1 showing the dental ingot in the process of being emitted in the direction of the illustrative arrow thereon;

FIG. 5 is a bottom partial view of the dispenser shown in FIG. 1; and

FIG. 6 is a top partial view of the dispenser shown in FIG. 1 showing internal parts in broken outline.

Referring now to the figures, there is shown in FIG. 1 a dispenser indicated generally at 10 according to the invention. It should be clearly understood that the dispenser 10 and all the component parts thereof are shown double-size in the figures for purposes of clarity, and that in the typical construction a dispenser according to the invention will occupy only about one-eighth the volume of a dispenser having the dimensions illustrated in the figures. That is to say, a dispenser according to the invention will typically be one and a fraction inches long and a fraction of an inch in transverse dimensions.

The dispenser 10 comprises a generally rectangular parallelopiped enclosure 11 having a top panel 12, a pair of side panels 13, 14, and a pair of end panels 15, 16, so that the enclosure 11 is open downwardly as may be clearly seen in FIG. 2. A bottom cover plate 17 of generally rectangular configuration is provided, having outside length and width dimensions very slightly greater than the inside length and width dimensions of the rectangular enclosure 11 at the bottom portion thereof. As may be partially seen in FIG. 2 in full outline and in FIG. 5 in broken outline, the lower inside edges of said panels 13, 14 are stepped or recessed at 13a, 14a to provide an indexing support surface for the bottom cover plate 17 when it is pressed into flush engagement between side panels 13, 14 and end panels 15, 16 to form a complete rectangular parallelopiped enclosure having two orifices therein presently to be described.

The rectangular enclosure 11, with the bottom cover plate 17 in place, and with other parts presently to be described housed therein, is intended to contain, in stacked relation, a plurality of individual dental ingots 20 in the form of flat rectangular, in the illustrated embodiment flat square, platelets of a precious metal suitable for dental work, e.g. gold. The individual ingots 20 have, in addition to relatively uniform major dimensions, a relatively uniform thickness, all to the end that a relatively precise amount of metal is contained in each ingot 20, so that the amount of metal employed by a given dental technician or other user of the ingots can be controlled and metered. In addition, the relatively precise dimensions of the ingots 20, and particularly the relatively precise thickness thereof, allows a seat and precise dispensing action, as will presently be described.

In top panel 12 is formed an aperture 25 which performs a dual function. The aperture 25 is defined by a slot portion 25a (FIG. 2) which is located in the portion of top panel 12 immediately adjacent the inner face of end panel 15, and an intersecting window portion 25b

extending at right angles to slot portion 25a for approximately one-half the length of the top panel 12 and having a fraction of the transverse width of slot portion 25a. It will be understood that slot portion 25a is slightly greater in its major opening dimension than the transverse dimension of one of ingots 20, and that it is slightly greater in its minor opening dimension than the thickness of one of ingots 20. Moreover, the major edge of slot 25a closest to end panel 15 is aligned with the inner face of end panel 15, so that an ingot 20 resting against the inner face of end panel 15 can slide smoothly along the inner face of end panel 15 out of slot portion 25a (FIG. 3).

In end panel 15 is located an aperture 15a (FIGS. 2 and 3) which serves as a finger hole for touching the most adjacent one of ingots 20 to slide it upwardly out of slot portion 25a. Aperture 15a is bordered adjacent top panel 12 by an inwardly beveled edge 15b, and adjacent side panels 13 and 14 by inwardly beveled edges 15c, 15d respectively (FIG. 4). Aperture 15a extends downwardly to intersect with the downwardly open bottom of enclosure 11 (FIG. 2), so that aperture 15a is bordered on three sides by beveled edges 15b-15d, forming a three sided frame for retaining an ingot 20 at the inner face of end panel 15. The bottom cover plate 17 includes a rectangular notch 17a-17c (FIG. 2) at the end thereof lying adjacent to aperture 15a when plate 17 is set into place at the underside of enclosure 11. The notch end faces 17a, 17c are approximately as deep as the thickness of an ingot 20, and the main notch face 17a is not as wide as the transverse dimension of an ingot 20, and preferably it is as wide as the opening 15a between lateral beveled edges 15c, 15d. Since the notch 17a-17c is not as wide as an ingot 20, the ingot 20 cannot be slid downwardly out of notch 17a-17c when plate 17 is in place in enclosure 11. However, notch 17a-17c is wide enough to cooperate with aperture 15a so that the bottom edge 20a (FIG. 3) of the ingot 20 resting against the inner face of end panel 15 can be intercepted by a finger introduced into aperture 15a at the lower portion thereof adjacent plate 17 to start the upward movement of the ingot 20. This is somewhat more convenient and efficient than employing only finger friction against the major face of the leading ingot 20.

A plunger member 30 having an L-shaped outline formed by a short leg portion 31 and a longer leg portion 32 at right angles to portion 31 is provided for axial plunger movement within rectangular enclosure 11 in the direction of the major axis thereof. The short leg portion 31 has appropriate transverse dimensions to move smoothly and easily broadside within the transverse cavity of rectangular enclosure 11 with bottom cover plate 17 in place. To achieve this, short leg portion 31 should have transverse dimensions only slightly smaller than the inside dimensions of the aforesaid cavity. The longer leg portion 32 will preferably have essentially the same width as the short leg portion 31, and will have a major dimension or length preferably not greater than the distance from the inner face of end panel 16 to the most adjacent end of window portion 25b. The plunger member 30 is inserted into the cavity within rectangular enclosure 11 through the bottom opening thereinto when the bottom cover plate 17 is removed in the general orientation shown in the exploded view of FIG. 2, so that the longer leg portion 32 is in flush contact with the inner face of the top panel 12, with the short leg portion 31 oriented toward the end panel 15.

Disregarding for the moment the ingots 20, the plunger member 30 is thereby capable of moving along the longitudinal axis of the cavity in rectangular enclosure 11 between two extremes, the first of which finds the short leg portion 31 lying flush against the inner face of end panel 15, and the other one of which finds the free end 32a of longer leg portion 32 in abutment with the inner face of end panel 16, this latter position involving the short leg

portion 31 lying sufficiently close to the end panel 16 so that it is withdrawn from the portion of top panel 12 occupied by window portion 25b, i.e. so that it is no longer visible through window portion 25b. A compression spring 35 is provided for biasing the plunger member 30 toward the first position just described, i.e. toward abutment with the inner face of end panel 15.

The free length of compression spring 35 should be greater than the distance between the inner faces of end panels 15 and 16 and the diameter, pitch, and material of the spring 35 should be such that it can be housed within rectangular enclosure 11 with the bottom cover plate 17 in place and provide a desired degree of force upon plunger member 30 even when it is in the first of the above-mentioned positions, i.e. in abutment of the inner face of end panel 15. Furthermore, the pitch and other characteristics of spring 35 should be such that the spring does not bottom within the range of movement already described for plunger member 30, i.e. so that the spring does not bottom up to and including the point where the plunger member 30 abuts the free end 32a thereof against the inner face of end panel 16.

With the plunger member 30 and spring 35 in place as has just been described and as is illustrated in the figures, there is provided a variable cavity between the short leg portion 31 of the plunger member 30 and the inner face of end panel 15. The plunger 30 is biased by the spring 35 so that it tends to minimize the longitudinal dimension of this cavity. It will be noted that viewed from outside top panel 12, the compression spring 35 is never visible when the internal parts are in place, because the longer leg portion 32 of plunger member 30 shields the spring 35 from view in all positions of the plunger member 30. This is an important feature of the invention.

The dispenser 10 is intended to be employed, as aforesaid, with a plurality of dental ingots 20 of precious metal. Conveniently, the dimensions of the dispenser 10 can be arranged so that a prescribed number of ingots 20 are to be accommodated, e.g. ten ingots 20. Under these circumstances after the internal parts 30, 35 have been assembled as aforesaid, the ten ingots 20 will be stacked and the plunger 30 will be manually pushed against the bias spring 35 until the free end 32a abuts the inner face of end panel 16. It is a feature of the invention that, if desired, automatic counting of the ingots 20 initially inserted into the dispenser 10 can be provided at this point. That is to say, when the end portion 32a abuts in the manner just described, a known distance will exist between the inner face of end panel 15 and the face of short leg portion 31 of plunger member 30 opposite thereto. This distance can be arranged, in a given instance, to equal the stacked height of a known number of ingots 20. For example, the distance just described can equal the stacked height of ten ingots 20. In that case, moving the plunger 30 to the position where end 32a abuts the inner face of end panel 16 allows the insertion of precisely ten ingots, and accordingly automatically provides a counting function if desired.

After the plurality of ingots has been inserted, the bottom cover plate 17 is pressed into place so that its outer surface is flush with the edges of panels 13-16 and so that notch 17a-17c lies under aperture 15a, and the dispenser 10 is ready for the dispensing of individual ingots 20. The individual ingot 20 abutting the inner face of end panel 15 will be immediately adjacent to and aligned with the slot portion 25a in top panel 12, and if the fingertip or another object controlled by the user is inserted through aperture 15a into contact with the broad surface of that ingot, or under the edge 20a thereof of lying above notch 17a-17c, the ingot can be slid upwardly to egress through the slot portion 25a in the manner shown in process in FIG. 1 and in the direction indicated by the illustrative arrow applied to the ingot 75 in question in that figure. It will be understood that

as soon as the ingot in question has been cleared of slot portion 25a the compression spring 35 will have driven the next adjacent ingot 20 against the inner face of end panel 15 to occupy the position just left by the previously dispensed ingot.

It is an additional and important feature of the invention that the quantity of ingots not yet dispensed is clearly visible through the window portion 25b in top panel 12. That is, when the full complement or initial loading of ingots 20 is in place, the plunger 30 will be driven out of sight as viewed by the window portion 25b, and there will be seen therethrough, to continue the illustration mentioned above, ten ingots 20. As the ingots 20 are individually dispensed, the plunger 30 will move further and further toward the inner face of end panel 15, and as viewed through window portion 25b there will be seen a correspondingly greater portion of the longer leg portion 32 of plunger 30. There is thus provided not only a clear view of the quantity of ingots 20 not yet dispensed, but also a clear view of the quantity already dispensed as represented by the portion of longer leg portion 32 visible through window portion 25b.

For example, if in looking through window portion 25b the visible portion of longer leg portion 32 is equal in length to the length along the remaining stack of ingots 20, then the inference can quickly be drawn that one-half of the original stack of ingots 20 has been dispensed. It is always possible to count the number of ingots 20 not yet dispensed by viewing them through the window portion 25b, but it is an additional and important feature of the invention that for the reason just described, the dispenser 10 according to the invention allows the proportion or quantity of ingots 20 remaining to be quickly estimated at a glance. To that end, it is convenient to provide the surface of longer leg portion 32 facing window portion 25b with a color which is sharply contrasting to the color of the ingots 20. For example, the color black can be provided to contrast with the color gold in the case of gold ingots 20. This makes it very easy to see at a glance what proportion of ingots 20 remain.

The dispenser 10 is intended to be a throw-away item used as a package as well as a dispenser for the dental ingots 20. It can however serve as a re-usable dispenser if desired, by the simple expedient of removing bottom cover plate 17 and inserting a fresh stack of ingots 20 in the manner already described.

By the use of dispenser 10 a careful control is possible of the amount of precious metal given to each dental technician in a laboratory for the purpose of making dentures. Further, there is provided a means for safeguarding or at least not misplacing the ingots 20 on the part of the dental technician himself. Moreover, there is provided a very convenient means of keeping track of the number of ingots used so that procurement of a new batch, by the technician is forewarned and facilitated. And yet, despite this, the dispenser 10 is fabricated from only four parts which can be very simply and economically manufactured in plastic except for the spring 25, which should of course be in an appropriate spring material (not excluding plastic) so that it is feasible to provide it as a throw-away item, if desired. This is a unique combination of qualities which provides a highly desirable expedient in this art.

The invention has been described with reference to a presently preferred but merely illustrative embodiment thereof, and it will be understood by those skilled in the art to be illustrative, not limiting.

What is claimed is:

1. A dispenser-package for flat, rectangular dental ingots, comprising:

(a) an enclosure for holding a plurality of said ingots in stacked relation, including

(i) a transverse dispensing slot in one longitudinal panel of said enclosure aligned with the inner

face of one end panel of said enclosure, said slot having dimensions allowing only one said ingot at a time therethrough edgewise,

(ii) an elongated window in said one longitudinal panel, intersecting said slot and extending along said one longitudinal panel part of the way toward the inner face of the end panel of said enclosure remote from said one end panel, and (iii) an aperture in said one end panel sufficiently large so as to allow access therethrough with a fingertip, but sufficiently small so that one of said ingots can be retained broadside against the remaining stack of said one end panel,

(b) a plunger for longitudinal movement within said enclosure, including

(i) transverse means facing said one end panel, and adapted to bear against that one of said stack of ingots most remote from said one end panel and said slot, and

(ii) longitudinal means connected to said transverse means, comprising a panel adapted to slidably lie against or adjacent to the inner face of said one longitudinal panel, and having sufficient width and length to completely underlie and thereby cover said window when said transverse means is in contact with the inner face of said one end panel, and

(c) a compression spring contained within said enclosure bearing upon said transverse means and the inner face of the end panel remote from said one end panel, to bias said plunger toward said one end panel inner face.

2. A dispenser-package according to claim 1, wherein the length of said plunger longitudinal means is additionally such that the entire plunger can be moved far enough away from the inner face of said one panel to be withdrawn completely from beneath said window.

3. A dispenser-package according to claim 2, wherein the length of said plunger longitudinal means is the same as the length of said one longitudinal panel of said enclosure from the end of said window remote from said one end panel to the inner face of said end panel remote from said one end panel, so that when said plunger is bottomed against said remote end panel inner face a certain number of ingots can be stacked between said plunger transverse means and the inner face of said one end panel, and all of these ingots and no portion of the plunger will be visible through said window, thereby allowing quick visual estimate of the proportion of ingots dispensed or remaining by comparing the proportion of ingot stack versus the proportion of plunger longitudinal means visible through said window.

4. A dispenser-package according to claim 3, wherein the color of said plunger longitudinal means is selected to contrast visually with the color of said ingots.

5. A dispenser-package according to claim 1, wherein the longitudinal panel of said enclosure opposite to said one longitudinal panel is removable for gaining access to the interior of said enclosure.

6. A dispenser-package according to claim 5, wherein said removable longitudinal panel is press-fit to said enclosure between the remaining two longitudinal panels.

7. A dispenser-package according to claim 6, wherein there is provided, along the adjacent inner edges of each of said two longitudinal panels, a stepped recess, so that said removable longitudinal panel is held flush with said inner edges by said stepped recesses.

8. A dispenser-package according to claim 5 wherein said aperture in said one end panel extends completely to the extreme edge thereof adjacent said removable longitudinal panel, and wherein said removable longitudinal panel includes, at the end thereof adjacent said aperture, a notch about as thick but not as wide as one of said ingots, so that said aperture and said notch combine to allow the ingot against the inner face of said one end panel

located remote from said slot to be contacted with the finger to start the sliding ejection of that ingot out of said slot.

9. A dispenser-package according to claim 1, wherein said plunger is L-shaped in action, said transverse means being the shorter panel, and said longitudinal means being the longer panel secured thereto at a right angle.

10. A dispenser-package according to claim 9, wherein said enclosure, and said plunger are fabricated in plastic.
